UNITED STATES PATENT OFFICE.

HASSEL D. ROBINSON, OF WASHINGTON, DISTRICT OF COLUMBIA.

DESIGN FOR A TRAFFIC-SIGNAL CASING.

Application filed January 6, 1925. Serial No. 11,936. Term of patent 7 years.

To all whom it may concern:

Be it known that I, HASSEL D. ROBINSON, a citizen of the United States of America, residing at Washington, District of Columbia, have invented a new, original, and ornamental Design for a Traffic-Signal Casing, of which the following is a specification, reference being had to the accompanying drawing, forming a part hereof.

The drawing is a perspective view of a traffic signal casing showing my design.

I claim:

The ornamental design for a traffic signal casing, as shown.

HASSEL D. ROBINSON.
